(57) **CLAIM**

The ornamental design for the propane tank cover, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of a propane tank cover embodying the design;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The dash-dot broken line showing of a propane tank, hose, and hose strap, is for the purpose of illustrating environmental structure and forms no part of the claimed design. The evenly dashed broken line showing of stitching on the propane tank cover is for the purpose of illustrating portions of the article and forms no part of the claimed design. The shading lines used in the drawings are for the purpose of illustrating surface contour and form no part of the claimed design.
